CLAIM

We claim the ornamental design for a railed forearm for AR-15 style rifles, as shown and described.

DESCRIPTION

FIG. 1 is a front perspective view of a railed forearm for AR-15 style rifles, showing our new design;

FIG. 2 is a rear perspective view thereof;

FIG. 3 is a left-side elevational view thereof, the right-side elevational view being a mirror image thereof;

FIG. 4 is an enlarged front elevational view thereof;

FIG. 5 is an enlarged rear elevational view thereof;

FIG. 6 is a top plan view thereof; and,

FIG. 7 is a bottom plan view thereof.
